UNITED STATES PATENT OFFICE.

JOSEPH P. WILSON, OF OGDENSBURG, NEW YORK.

DASH-LIGHT FOR AUTOMOBILES.

1,188,596.

Specification of Letters Patent. Patented June 27, 1916.

Application filed January 14, 1916. Serial No. 72,084.

To all whom it may concern:

Be it known that I, JOSEPH P. WILSON, a citizen of the United States, residing at Ogdensburg, in the county of St. Lawrence and State of New York, have invented certain new and useful Improvements in Dash-Lights for Automobiles, of which the following is a specification.

The invention has for an object to provide a desirable form of dash appliance for motor vehicles, and seeks to effect an improvement in the construction of a switch and choke coil combined for use on a magneto and battery alternatively.

An important object is to provide a novel arrangement of elements whereby the lighting of a lamp from the magneto current will not appreciably dim the brilliancy of the headlights which also derive current from said magneto.

A further important object is to provide a novel form of light casing.

It is also an object to provide a device in which a light holder is combined in an efficient manner with the light support and switch.

It is also an object to give an improved specific attaching means for fixing the device on a dash of that kind generally termed the "cowl" dash, being adapted to be secured upon the innermost part of the cowl portion without obstructing the space thereunder objectionably, and without requiring the drilling of holes or other special operations.

Additional objects, advantages and features of invention will appear from the construction, arrangement and combination of parts hereinafter set forth and shown in the drawings where,

Figure 1 is a vertical sectional view of my appliance in use upon a familiar type of cowl dash, the inner edge of the cowl only being shown, Fig. 2 is a bottom view thereof, Fig. 3 is an outer or front elevation of the bracket piece, Fig. 4 is a rear elevation of the complete device, Fig. 5 is a side view partly in section of a device arranged to hold a watch in a vertical plane, and being otherwise substantially the same as the device illustrated in the first described figures. Fig. 6 is a perspective view of a modification of the bracket.

There is illustrated the upper inner edge portion of a cowl 10, upon which the glass wind shield and frame 11 are supported in

a familiar way, the cowl being formed of sheet metal, with a shoulder 12 projecting upwardly from the lower part of the wind shield 11, whence the metal of the cowl is extended downwardly a distance forming a vertical edge plate 13, the lower edge portion of the metal being turned upwardly a short distance forwardly of this plate, as at 14.

A bracket element is provided including a body having the forward or upper side 15, formed with a plane inner surface adapted to lie flat against the plate 13, and having a horizontal rearwardly projected lip 16 adapted to engage over the shoulder 12 of the cowl. Projected inwardly from the part 15 and a distance below the lip 16 somewhat greater than the vertical width of the plate 13, there is a horizontal plate 17, from which there extends upwardly an arm 18, parallel to and so spaced from the part 15 as to lie some distance inwardly of the upturned portion 14 of the edge of the cowl. A wing screw 19 is engaged through the upper part of this arm, adapted to be screwed into forcible engagement with the plate 13 or any interposed body. The plate 17 is formed with resilient suitably spaced clamp arms or jaws 20, shaped and adapted to be drawn together by means of a bolt 21, to hold therebetween the tubular casing 22 of a combined switch, choke coil and lamp socket now to be described.

The casing 22 is cylindrical, and may be formed of sheet metal or of ordinary drawn tubing, as found most desirable and convenient. The outer or forward end—that which is next the observer when the device is in use—is formed with the familiar bayonet slot 23, for the reception of the base of an electric lamp 24, having the usual trunnions 25 on each side for engagement in the slot. The inner or rear end of the casing 22 incloses a spool 26 of suitable insulating material having a choke coil winding 27. The spool is centrally bored as at 28, and on the forward end is provided with two screws or plugs 29, one of which has connected thereto a wire 30 extending through the central bore of the spool, while the other has connected thereto a wire 31 leading through the coil 27. The spool 26 is fixed in the casing by having part of the casing indented to project partly into the body of the spool at each end, as shown at 32.

A small plug 33 of insulating material is fitted loosely and revolubly in the casing, having a spring pressed contact plunger 34 of a familiar form mounted centrally 5 thereof and projecting forwardly for engagement upon the central contact 35 of the lamp base 24. A small screw or contact post 36 is engaged in the plug 33, and suitably connected to the plunger 34, the plug 10 36 being spaced from the center of the casing a distance corresponding to the spacing of the plugs 29, which are each spaced the same distance from the center of the casing. A slot 37 is formed in the side of the 15 casing intermediately the length of the plug 33 when at the inner limit of its movement, and engaged in the plug for oscillation in this slot there is an operating lever 38 by which the plug may be turned to move the 20 contact 36 into engagement with one or the other of the contacts 29, normally being positioned intermediately thereof. If desired a small recess or notch may be formed in the inner end of the spool 26 25 spaced intermediately of the contacts 29, so that the plug will be held yieldably in intermediate position without any circuit being closed. By this arrangement it will be seen that the plug 33 is held at the inner 30 limit of its movement by means of the engagement of the lamp socket with the spring pressed plunger mounted in the plug, whereby resilient contact between the elements 36 and 29 is attained without any 35 special resilient device.

A spherical lamp inclosure 40 is provided, formed of a suitable opaque material, fitted snugly around the outer forward end of the casing 22, and positioned concentri- 40 cally with respect to the lighting element in the lamp, or otherwise, as found desirable. This inclosure is preferably made removable from the end of the casing in order that the lamp may be renewed when necessary, with 45 facility. The inclosure 40 is provided with an enlarged opening 41, at the lower side suitable for the passage of light to illuminate a speedometer, levers, pedals and indicators which may be mounted on the dash 50 and therebeneath, while at the upper side an opening 42 is formed and a light fender flange 43 formed in the inclosure extending from adjacent the side of the opening nearest the casing 22 forwardly and inwardly within the inclosure, for a suitable 55 distance and stopping short just below the outermost part of the opening 42, so as to prevent passage of light from the lamp directly outward in such a direction as to 60 strike the eye of the motorist. The upper part of the bracket element may have an enlargement as at 44, with an inclined forward surface upon which a watch or clock may be secured as at 45, and held in con- 65 venient position for observation by the mo-

torist; and for illumination by light passing through the opening 42 of the lamp inclosure. In the present instance there is shown a watch 46 having a back 47 which fastens in the familiar way in many watches now 70 in use, this back being centrally apertured and a screw 48 engaged therethrough and in the enlargement 44, by which the watch is held in place.

As shown in Fig. 5 the bracket is without 75 the enlargement 44 before mentioned, and the watch is held in a vertical position and attached in the same manner as before mentioned. The opening 42 in the light inclosure may in this form of the device be located 80 farther inward with respect to the casing 22. Also, the casing 22 may be adjusted farther inward in the bracket between the clamping arms 20 so that the light is projected a shorter distance from the dash. In 85 the last mentioned figure also, the clamp arms are made somewhat narrower than shown in Fig. 1, and alined with the front part of the element 15 of the bracket. If desired the inner end of the casing 22 may 90 be slitted to form a multiplicity of tongues 49, which may be turned inwardly over the end of the spool 26 as shown in Figs. 1 and 4.

The bracket element and clamp arms with 95 the parts corresponding to those 15, 17 and 18 previously described may be formed integrally from sheet metal as shown in Fig. 6, and in case it is desired to mount the watch in an inclined position a central 100 tongue 50 may be stamped from the forward jaw piece 15^a corresponding to the part 15 before described.

The use of the device will be readily understood, the wire 30 being connected to one 105 terminal of a battery, the other terminal of which is grounded, while the wire 31 is connected to one of the terminals of the magneto, the opposite terminal of which is also grounded.

The inclusion of the choke coil providing means whereby an electric lamp of suitable candle power but of low voltage (2 candle power, four volts being ordinarily employed where the magneto ordinarily produces a 115 potential of twelve volts) is suitably lighted from the magneto current without appreciably dimming the head lights which are likewise connected to the said magneto, as would be the result if said head light lamps 120 and the one on the dash appliance were all of the same high voltage.

What is claimed:

1. In a device of the class described a cylindrical casing, a spool of non-conducting 125 material having a choke coil thereon, contacts on the spool, similarly spaced from its center, battery connections for one and magneto connections for the other leading through the coil, a plug of non-conducting 130

material loosely revoluble in the casing and having a contact element thereon positioned for alternative engagement with the first named contact on the spool, means to rotate 5 the plug, a spring pressed contact member in the plug electrically connected with the said contact member on the plug, a lamp having a base including a contact element for engagement against the spring pressed contact, and means for holding the base in said 10 casing adjacent the inner limit of its movement therein.

2. In a device of the character described a cylindrical casing, switch point contacts located adjacent one end thereof similarly spaced from its center and insulated therefrom, a plug loosely revoluble in the casing, a switch contact thereon positioned for alternative engagement with the switch points, 15 a spring pressed contact member carried by the plug and electrically connected to said named contact member on the plug, means to hold a lamp base in bearing on said spring pressed contact member, said casing having 20 a circumferential slot therein, and an operating lever engaged in the plug and projected through said slot.

3. A device of the class described comprising a bracket element having formed on 30 its upper portion securing devices for attachment to a dash or the like, and having resilient spaced arms projected downwardly therefrom, a cylindrical casing slidably engaged with the bracket, means to secure the 35 casing in the bracket, an electric lamp mounted at the outer end of the casing, a switch device in the casing, and an inclosure carried by the casing around said light having an opening 40 at its lower side, clear for direct passage of light from the lamp therethrough, and having an opening at its upper side, a light fender mounted across the last named opening diverging therefrom toward the forward part of the device, and a watch 45 support on the upper part of said bracket constructed to support a watch in the field of light passing through the said last named opening.

4. A dash light device for use alternatively with battery or magneto of the type indicated comprising a bracket element, including means for attaching it to a dash or the like, and having resilient arms projected laterally therefrom, a cylindrical casing element engaged between the arms, means to clamp the arms on the casing element, a resistance coil mounted on the casing, 50 concentrically spaced insulated switch points

within the casing inwardly of the resistance coil, battery connections to one and magneto 55 connections for the other the latter leading through the resistance coil, a rotating switch plug longitudinally slidable in the casing outwardly of the switch points and having a contact positioned for alternative engagement with the points, a slot being formed in the side of said casing, a lever on the plug projected through the slot and engaged removably with the plug, a resilient contact device mounted in the plug extending outwardly, and means to secure a lamp base in the outer end of the casing in engagement with said spring pressed contact.

5. A device of the character described comprising a bracket element for attachment to a dash or the like, a cylindrical casing slidably engaged with the bracket, means to secure the casing on the bracket, an electric lamp mounted in the outer end of the casing, a switch device associated with the 75 electric light, and an inclosure carried by the casing around said light having openings therein, a light fender adjacent one opening, and a watch support on the upper part of said bracket constructed to support a watch 80 in the field of light passing through the last named opening.

6. A dash light device comprising a bracket element including means for attaching it to a dash or the like, a light carrying element adjustably engaged upon the bracket, a light carried thereby, an inclosure for the light constructed to direct light in a predetermined direction, means to secure the light holder adjustably in the bracket, and 90 means to secure a watch or the like on the bracket in the field of light from said inclosure when in one position.

7. In a switch of the class described a casing, a switch point at its inner part, a movable switch member having a contact for engagement with the point at one position, a spring-pressed contact member at the outer side of the switch member, a lamp having a base including a contact element for engagement against the spring pressed contact, and means for holding the base in said casing in bearing on the spring pressed contact, and means to operate the switch member.

In testimony whereof I have affixed my 110 signature in presence of two witnesses.

JOSEPH P. WILSON.
